UNITED STATES PATENT OFFICE.

JOHN OMWAKE, OF CINCINNATI, OHIO, ASSIGNOR TO THE UNITED STATES PRINTING COMPANY, OF SAME PLACE.

DESIGN FOR A BACK FOR PLAYING-CARDS.

SPECIFICATION forming part of Design No. 23,135, dated March 20, 1894.

Application filed February 16, 1894. Serial No. 500,420. Term of patent 14 years.

To all whom it may concern:

Be it known that I, JOHN OMWAKE, a citizen of the United States, residing at Cincinnati, in the county of Hamilton, State of Ohio, 5 have invented and produced a new and original Design for the Backs of Playing-Cards, of which the following is a specification, reference being had to the accompanying drawing, forming part thereof.

10 The figure of the drawing represents the back of a playing card embodying my design.

The essential features of my design, consist in the representation of wheels within each

of which is the representation of a figure mounted upon a velocipede.

In the drawing, *a a* designate wheels which are inclosed by an ornamental scroll *b*, and in each of said wheels is the representation of a figure *c* mounted upon a velocipede *d*.

I claim—

The design for the backs of playing cards, substantially as shown and described.

JOHN OMWAKE.
